his Attorney.

United States Patent Office.

WILLIAM N. McINNIS, OF NORTHUMBERLAND, PENNSYLVANIA.

Letters Patent No. 74,925, dated February 25, 1868.

IMPROVEMENT IN SPRINGS FOR RELAY-MAGNETS.

The Schedule referred to in these Letters Patent and making part of the same.

TO ALL WHOM IT MAY CONCERN:

Be it known that I, WILLIAM N. McINNIS, of the town of Northumberland, county of Northumberland, and State of Pennsylvania, have invented Improvements in Electro-Magnetic Telegraphs, which I style the "Winding-Spring Telegraph-Relay Adjuster;" and I do hereby declare the following to be an exact description thereof, reference being had to the accompanying drawings, and to the letters of reference marked thereon, making a part of this specification, in which—

Figure 1 represents a side elevation of the machine.

Figure 2 a front view.

A represents the winding-wheel; B, the wheel-axle; D, the wheel-stand; E, the adjusting-screw; F, the screw-supporter; G, the relay-armature; H, the relay-frame; I, the relay-magnets; all of which are well-known devices belonging to electro-magnetic telegraphs.

The nature of my invention consists in the construction and attachment of a single or double irregularly-coiled steel spring, C, to the axle B (of the winding-wheel A) and to the relay-armature G, for the purpose of giving the extremes of elasticity and freedom to the armature G, imparting the most perfect fineness of adjustment, with strength and durability. One or more flat steel springs, C, are attached at each end to the axle B, as shown at J, and at the other end, as shown at L. They are then wound in a loose, irregular coil around the axle B, and toward the centre of the axle, where the two ends are joined permanently together, forming a tapering loosely-coiled spring, C, from where it enters the axle to the widest extremity, at M, where it is connected, by wire or otherwise, to the armature G, and by turning the adjusting-screw E the wheel A is turned, which will wind up spring C, giving the extremes of elasticity and freedom to the armature G. Thus the fineness of adjustment given by this winding-spring C supplies a want long felt in telegraphing, and lines can be worked with this attachment that cannot be used at all with the common adjuster. Owing to the scope of elasticity possessed by this winding-spring C, it gives to the relay-armature a capacity for fineness of adjustment, combined with all necessary strength, hitherto unknown, in consequence thereof dispensing with the necessity of having main batteries of over half the strength of those now in use, thereby causing a saving of at least one-half the battery-material used at present. The difficulties now experienced in telegraphing are completely overcome, such as "escapos," bad weather, or imperfect insulation; and numerous accidental and natural obstructions, that render the present system of adjustment useless, or work so hard as to be nearly so, can, with my adjuster, be worked with perfect ease and prevent the now experienced and numerous delays in the transmission of messages. This adjuster also retains its adjustive powers, so that officers will hear their respective calls, no matter what the difference may be in the electric current at each office.

What I claim as my invention, and desire to secure by Letters Patent, is—

The construction of the irregularly and loosely-coiled steel spring C, when attached to and combined with the winding-axle B and the armature G, as herein described and for the purposes set forth.

WM. N. McINNIS.
